United States Patent Office

Des. 181,871
Patented Jan. 7, 1958

181,871

PROJECTOR

John R. Miles, Glenview, Ill., assignor to Projection Optics Co., Inc., Rochester, N. Y., a corporation of New York

Application October 4, 1956, Serial No. 43,231

Term of patent 14 years

(Cl. D61—1)

FIG. 1.

FIG. 2.

FIG. 3.

FIG. 4.

Figure 1 is a side view in elevation of a projector showing my new design.

Figure 2 is a front elevational view.

Figure 3 is a rear elevational view.

Figure 4 is a top plan view thereof.

A portion of Figure 2 is diagonally lined to indicate transparency.

I claim:

The ornamental design for a projector, substantially as shown and described.
